UNITED STATES PATENT OFFICE.

SAMUEL RUBEN, OF NEW YORK, N. Y.

ELECTRON RELAY.

Application filed October 23, 1920, Serial No. 418,896. Renewed September 22, 1926.

This invention relates to a means for utilizing the kinetic energy of electrons in an exhausted tube, or electrons and ions in a tube which may contain more or less gas or vapor. In carrying out the invention, I provide, in a vacuum tube, the usual filament or electron emission element and a grid element, and a plate element which is movable by variations in pressure in the electron stream flowing from the emission element to said plate element. This movable plate element is connected in a receiving or signaling circuit, wherein it may function either as a means for opening and closing said circuit, or as a means for varying the resistance of the circuit when the volume, and therefore the pressure, of the electron stream flowing to the plate element is varied. If the plate element is arranged in close proximity to a contact member in a signaling circuit, the plate element may be used as a circuit making and breaking device, or, if arranged in actual engagement with a contact member, such as a granule of graphite, the plate member may be used as a means for varying the resistance of the signaling circuit in accordance with variations in the volume of the electron stream.

In the accompanying drawing, for the purposes of illustration, I have shown a sensitive microphone within a vacuum tube, the diaphragm of the microphone constituting the plate element. The impact of the electrons in the electron stream passing from the filament to the diaphragm exerts a pressure against the diaphragm, and this pressure is varied by the electrical impulses in the grid circuit, causing corresponding vibrations of the diaphragm. The microphone is connected in a signaling circuit provided with a battery and telephone receiver, or other signaling device, and the impulses in the grid circuit are repeated and amplified in the signaling circuit.

45 In the accompanying drawing,

Fig. 1 is a central section through a vacuum relay embodying my invention; and,

Fig. 2 is a diagram showing the connections of the relay in a radio circuit.

50 Referring to the drawing, 1 indicates the exhausted tube, 2 the electron emission element, and 3 indicates the grid element, which is preferably made in the form of a flat helix. A delicate microphone *m* is placed opposite the grid and the diaphragm

4 of the microphone constitutes the plate element of the tube. This plate element bears against a granule of graphite 5, which is supported against the diaphragm by a metal piece 6, connected to a conducting rod 7. 60 This rod carries a semi-spherical insulator 8, which supports the diaphragm 4. The diaphragm is very light in weight and delicately mounted so that it may vibrate like a telephone transmitter and thus cause variations in the resistance of the contact between it and the graphite. 65

In Fig. 2, I have illustrated diagrammatically the connections of the relay in a tuned radio circuit, which latter it is unnecessary to describe in detail. As shown in the diagram, the filament 2 and grid 3 are connected as usual in the filament and grid circuits, respectively, and the diaphragm 4 of the microphone is connected in 70 the plate circuit. The diaphragm and graphite button 5 are connected in a local circuit 9, which includes a telephone receiver 10 and a battery 11.

With the arrangement described, when the filament is heated, an electron stream will flow from the filament to the plate, and the impact of the electrons against the plate causes a pressure against the plate which lessens the resistance of the contacts of the 80 microphone and therefore increases the current flow in the circuit 9. The volume of the electron stream, and therefore its pressure against the plate, will, however, vary in accordance with the impulses in the grid 85 circuit and this will cause corresponding vibrations of the plate or diaphragm. The vibration of the diaphragm, as will be understood, will cause variations in the resistance of the contacts of the microphone and corresponding variations in the flow of current 90 in the circuit 9, and amplified signals corresponding to those in the grid circuit will be relayed in the local circuit. 95

Any suitable form of microphone may be 100 employed and the relay as a whole may be used with aerial circuits connected in various ways for telephoning, telegraphing or signaling. By the term plate element in the claims I mean the element to which the electron stream flows from the emission element, regardless of the form or substance of the former element. While in a well exhausted tube the relay functions purely by electronic 105 emission, it will be understood that in a tube 110

containing more or less gas there may be a combined electronic and ionic emission due to the impact of the electrons upon the gas particles.

5 What I claim is:

1. An electron relay comprising an electron emission element, a receiving circuit, means for varying the resistance in said circuit comprising a plate element movable in 10 response to the kinetic energy of the electron stream issuing from said emission element, and means for varying the electron flow from the emission element to the plate element.

15 2. An electron relay comprising a vacuum tube having therein an electron emission ele-

ment, a grid element and a microphone comprising two contacting members one of which functions as a plate element.

3. An electron relay comprising a vacuum 20 tube having therein an electron emission element, a grid element and a microphone transmitter, the latter having a diaphragm constituting a plate element.

4. An electron relay comprising a vacuum 25 tube having therein an electron emission element, a grid element, a vibratory diaphragm constituting a plate element, and a contact member adapted to be engaged by the diaphragm.

In testimony whereof I affix my signature.

SAMUEL RUBEN.
